UNITED STATES PATENT OFFICE.

WILLIAM S. STACY, OF ASHLAND, OREGON.

CONCENTRATOR.

1,410,616.

Specification of Letters Patent. Patented Mar. 28, 1922.

Application filed March 4, 1919. Serial No. 280,607.

To all whom it may concern:

Be it known that I, WILLIAM S. STACY, a citizen of the United States, residing at Ashland, in the county of Jackson and State 5 of Oregon, have invented certain new and useful Improvements in Concentrators, of which the following is a specification.

The invention relates to ore concentrating machinery of the type in which the ore is 10 separated by a combined washing and jiggling motion, the concentrates and tailings being carried off through suitable conduits by means of a pumping mechanism.

The drawings illustrate a preferred embodiment of the invention. However, it is 15 to be understood that in adapting the same to meet different conditions, various changes in the form, proportion, and minor details of construction may be resorted to without 20 departing from the nature of the invention as claimed hereinafter.

In the drawings hereto attached,

Fig. 1 is a side view of an ore concentrator embodying the invention.

25 Fig. 2 is a top plan view.

Fig. 3 is a vertical longitudinal section.

Fig. 4 is a transverse section on the line 4—4 of Fig. 2, looking in the direction of the arrows.

30 Corresponding and like parts are referred to in the following description and indicated in the several views of the drawings by like reference characters.

As indicated the machine is mounted upon 35 trucks so as to be readily transported from one place to another. The numeral 1 designates the body of the machine and the same is constructed after the manner of a box or tank so as to contain water and receive the 40 separating mechanism. A chute 2 is located at one end of the body and is adapted to receive the ore and direct the same into a hopper 3 located at one end of the machine and elevated above the body thereof. The hopper 45

per 3 extends approximately the entire width of the body 1 and underlaps the delivery end of the chute 2 so as to receive the material therefrom. The chute 2 embodies passages 4 which diverge toward their delivery ends 50 so as to supply the material to the hopper 3 throughout its length. The chute 2 is mounted upon the body 1 whereas the hopper 3 is mounted upon the shoe or frame 5 of the separating mechanism.

55 The shoe comprises a suitable frame 5 which is supported by means of hangers 6

which are connected at their lower ends to the frame 5 and are mounted at their upper ends in standards 7 secured to and projecting upward from the body 1. A pan 8 is 60 disposed beneath the frame 5 and is transversely curved, the receiving end of the pan being closed and its delivery end opened, as indicated most clearly in Fig. 3. This pan catches the tailings and other material discharging from the strides of the separating tables. Brackets 8^a support the hopper 3 and are connected at their lower ends to the frame 5 and at their upper ends to a cross piece 9 secured to the under side of the hopper and which has its ends projecting so as to overlap the upper reinforced edges of the sides of the body 1. A transverse shaft 10 is mounted in standards 11 carried by a cross piece 12 secured to the sides of the body 75 1. The shaft 10 is adapted to be driven from a suitable source of power in any well known way and is provided with a crank portion which is connected by means of a pitman 13 to a rod 14 attached to the rear 80 side of the hopper 3. In this manner the shoe and separating mechanism have a jiggling or vibratory movement imparted thereto. A rod or bar 15 is connected at one end to the hopper 3 and its opposite end passes 85 loosely through a member 16 and receives buffers 17 upon opposite sides of the member 16 so as to control the jiggling motion and prevent undue shock and wear to the moving parts.

90 The hopper 3 is closed at its ends and rear and is provided with separating screens 18 and 19 of different mesh. Pipes 20 lead from end portions of the bottom of the hopper to deliver the material to the separating 95 mechanism. By having the front side of the hopper open above the separating screens 18 and 19 large pieces of material will automatically discharge and thereby prevent choking of the hopper.

100 The separating mechanism embodies two tables which taper throughout their length, as shown most clearly in Fig. 2. Each of the tables comprises a head portion 21, an intermediate portion 22 and a tail portion 105 23; the head portion 21 is covered by means of a perforated hood 24 with which the pipe 20 connects. The intermediate portion 22 is studded with pins. The tail portion 23 is longitudinally fluted. The separating 110 tables are connected with the shoe so as to vibrate therewith.

Each table has its component parts in the same plane and is adapted to discharge at the rear and sides. The material discharging at the sides of the tables is received in 5 the pan 8 and directed by it to the rear of the tank 1. The material discharging from the rear of the tables is received directly by the tank 1.

A box 25 is disposed upon the inner side 10 of the rear wall of the body 1 to receive the concentrates from the separating tables. A tailings box 26 is disposed beneath the rear end of the body and a gate 27 controls the delivery of the tailings from the body 1 into 15 the box 26. The concentrates from the body 25 are adapted to be drawn therefrom by means of a pump 28 and the tailings from the box 26 are adapted to be drawn off by means of a pump 29. The pumps 28 and 29 20 are shown as consisting of the rotary type and the material drawn off thereby may be delivered at any determinate point.

The separating mechanism is submerged in water contained in the body 1 and when 25 the machine is in operation, a jiggling or vibratory movement is imparted to the shoe and attached parts. The material supplied to the chute 2 is delivered thereby into the hopper 3, the small particles passing through 30 the screens 18 and 19 and the particles too large to pass through the screen 18 automatically discharging. The material passes from the hopper through the pipes 20 to the hooded portions of the separating tables, 35 the ore being disengaged from the earthy matter by means of the pins or studs on the intermediate portion 22 of the separating tables and the metal passing along the grooved portion 23 of the tables and discharging into the box 25. The earthy matter 40 spreads out and discharges from the sides of the tables into the pan 8 and collects in the bottom of the body 1 from which it is discharged at required intervals by open-

ing the gate 27. The boxes 25 and 26 are 45 kept clear by means of the pumps 28 and 29.

The pump 28 returns the concentrates by pipe 28^a to the front of the machine where they are delivered to a suitable table. The pump 29 has a pipe 29^a for conveying 50 the tailings to a flume or other point of discharge.

The foregoing description and the drawings have reference to what may be considered the preferred, or approved form of 55 my invention. It is to be understood that I may make such changes in construction and arrangement and combination of parts, materials, dimensions, et cetera, as may prove expedient and fall within the scope 60 of the appended claim.

Having thus fully described my invention, what I claim as new and desire to secure by Letters Patent is:—

A separator, comprising a frame mounted 65 to receive a reciprocating movement, a plurality of separating tables mounted on the frame, each having a rear end and side delivery and comprising head, intermediate and tail portions, the intermediate portion 70 being studded with pins only and the tail portion being longitudinally fluted, hoods disposed over the head portions of the tables and mounted on the said frame to move therewith, a pan beneath the tables to receive 75 the material discharged laterally therefrom and carried by said frame, a hopper mounted on the frame and located above the said hoods and adapted to receive the material and deliver the same to the head portions 80 of the separating tables, and separating screens in the hopper.

In testimony whereof I affix my signature in presence of two witnesses.

WILLIAM S. STACY.
